UNITED STATES PATENT OFFICE.

JOHN P. NIKONOW, OF BALTIMORE, MARYLAND.

WRENCH.

1,302,834.

Specification of Letters Patent.

Patented May 6, 1919.

Application filed July 9, 1918. Serial No. 244,056.

To all whom it may concern:

Be it known that I, JOHN P. NIKONOW, a Russian citizen, and resident of the city of Baltimore and State of Maryland, have invented a new and useful Improvement in Wrenches, of which the following is a specification.

My invention relates to the wrenches and has for its object to provide a simple and effective device of this character, having adjustable jaws and made of steel stampings. A further object of the invention is to provide a wrench of a thin type, especially adapted to be used in places, where access to the work is difficult.

In the accompanying drawings Figure 1 is an elevation of my wrench, Fig. 2—longitudinal section through A—B, Fig. 3—section, showing method of holding an operating screw, Fig. 4—enlarged end view partly in section, showing a modification of my invention. Figs. 5 and 7 show separately stampings 1 and 2, and Fig. 6 is a longitudinal section of stamping 2. Fig. 8 is an enlarged and exaggerated view of the operating parts of my wrench, showing main principles of my invention.

The main body of my wrench consists of two sheet metal stampings 1 and 2, welded or riveted together. These stampings form on the ends a stationary jaw 3 and a handle 4. In the middle a space 5 is formed for the movable jaw 6, also space 7 for the adjusting screw 8. The movable jaw 6 has teeth or threads 9 formed on its edge, fitting into the threads of the screw 8. The screw 8 has a thumb handle 10 to turn it by hand, and turning of this screw moves the jaw 6 in or out. A movable jaw extension is partly cut away to provide a clearance for the thumb handle. In order to prevent a longitudinal movement of the screw itself, it has a groove or a recess 11, and the edges of the stampings 1 and 2 are bent into this recess, as is shown on Fig. 3. In order to guide the movable jaw 6, especially when it is moved out, it has a groove 12, into which fits a depression or projection in the stamping 1. This groove ends at a proper distance so as to prevent the excessive extending of the movable jaw. The extension of the movable jaw acts as a guide, when the jaw is moved out, also as a lever, helping to wedge the movable jaw against the screw, when the wrench is in operation. A modification of this arrangement is shown on Fig. 4, consisting of

a pin 13, driven into the movable jaw in a suitable place, and grooves 14 in the stampings 1 and 2, which serve as guides for the pin. As an additional guide, the edge 15 of the movable jaw may be enlarged so as to fit partly in the space 7 for the screw.

The adjusting screw 8 extends through the full length of the space 7, resting with its threads against the walls of this space, no other bearings being necessary to support this screw 8. The threaded portion of the screw 8 is longer, than the notched portion of the jaw 6, so that full length of the movable jaw 6, which is inside of the space 5, is engaged with the screw. The engaged portion varies in length, depending upon the position of the movable jaw 6.

The working pressure between the jaws tends to press the outward end of the movable jaw against the screw 8, which is tightly wedged between the jaw 6 and the walls of the space 7. As it may be seen from the Fig. 8, this is caused by the shank 13 of the jaw 6 fulcruming on the inside outward end of the space 5, and the outward end of the notched portion of the jaw 6 fulcruming upon the screw 8, as shown by arrows 14 and 15. The pressure thus exerted on the screw 8 is transmitted directly against the walls 7 (arrow 16), so that screw 8 is subjected only to the compressive strain and no bending. The point of the maximum pressure varies with the position of the movable jaw 6.

Such distribution of forces allows for a very light construction of the screw 8, and it may be made very thin with ordinary sharp threads.

Fig. 8 is exaggerated for the purpose of clearness, and it is not supposed, that the jaw 6 may in any point become so widely separated from the screw 8.

Important advantages of my wrench are, that it can be cheaply manufactured in quantities, is light, thin, and convenient for operation.

I claim as my invention:

1. In a wrench, the combination with a flat body member composed of two flat pieces, fastened side by side having near its outer end a wide portion provided with a transverse approximately cylindrical screw receiving passage extending across said wide portion, the outer end of said wide portion being cut away to form a fixed jaw, said wide portion also being provided with a transverse shank receiving passage of ap-

proximately rectangular cross section and communicating with said screw receiving passage and extending to said fixed jaw; a screw extending from end to end of said 5 screw receiving passage, threads of said screw resting against the inside walls of said screw receiving passage, and a movable member having a movable jaw opposite said fixed jaw, and a shank disposed in said shank receiving passage, the lower edge of said shank being provided with thread-teeth adapted to engage a more or less longer portion of said screw, depending upon the position of said movable member and fulcrum upon the extreme outer end of said screw, the upper edge of said shank engaging and fulcruming upon the upper part of said shank receiving portion, so that when said jaws are subjected to the working pressure, said 10 shank will fulcrum upon said portion and force said thread-teeth into a firm engagement with said outer end of the screw pressing at the same time the threads of said screw against the inside walls of said screw receiving passage directly opposite the point of pressure.

2. In a wrench, the combination with a flat body member having near its outer end a wide portion provided with a transverse 15 approximately cylindrical screw receiving passage extending across said wide portion, the outer end of said wide portion being cut away to form a fixed jaw approximately parallel and near to said axis, said wide portion also being provided with a transverse shank receiving passage of approximately 20

rectangular cross section and communicating with said screw receiving passage and extending to said fixed jaw; a screw extending from end to end of said screw receiving passage, threads of said screw resting against the inside walls of said screw receiving passage, a means to prevent said screw from being moved axially, and a means to turn said screw by hand, and a movable member having a movable jaw opposite said fixed jaw, and a shank disposed in said shank receiving passage, the lower edge of said shank being provided with thread-teeth adapted to engage and fulcrum upon the extreme outer 45 end of said screw, the upper edge of said shank engaging and fulcruming upon the upper part of said shank receiving portion most remote from said extreme outer end, so that when said jaws are subjected to the 50 working pressure, said shank will fulcrum upon said remote portion and force said thread-teeth into firm engagement with said outer end of the screw, pressing at the same time the threads of said screw against the 55 walls of said screw receiving passage directly opposite the point of pressure, said point of pressure being more or less near the edge of said screw receiving passage depending upon the position of said movable member.

In testimony whereof I have hereunto subscribed my name this 6th day of July, 1918.

JOHN P. NIKONOW.
